UNITED STATES PATENT OFFICE.

JOHN Q. SLYE AND RICHARD H. COFFREN, OF WASHINGTON, DISTRICT OF COLUMBIA.

ACOUSTIC DIAPHRAGM.

Application filed December 16, 1926. Serial No. 155,220.

This invention relates to improvements in sound reproducing instruments and more particularly to a novel diaphragm for talking machines, loud speakers and the like.

With a view of improving sound reproduction instruments and to obtain better results, various kinds of diaphragms have been devised. Some of these are made up of laminated layers. The present invention relates more specifically to diaphragms of the last mentioned type.

One of the objects of the invention is to provide a diaphragm made up of at least three layers, each playing an important part with tone vibrations in musical records and the like. One layer preferably consists of double-faced satin, and this is combined with a second layer of thinly rolled tin foil, these two layers combining to give rich tone quality to the music and dampening the metallic ring usually present in talking machines and the like. The third layer preferably consists of a circular piece of cork which modifies the great friction which is usually associated with talking machine records.

With the foregoing object outlined and with other objects in view which will appear as the description proceeds, the invention consists in the novel features herein-after described in detail, illustrated in the accompanying drawing, and more particularly pointed out in the appended claims.

Referring to the drawing:

Fig. 1 is a face view of a standard talking machine reproducer provided with the improved diaphragm.

Fig. 2 is a vertical sectional view taken on line 2-2 of Fig. 1.

Fig. 3 is an enlarged vertical sectional view of a portion of the diaphragm, to clearly illustrate the arrangement of the layers.

In the drawing, 1 designates a talking machine reproducer, which may be of any preferred construction, to be combined with the improved diaphragm, the latter being connected to the usual stylus 3.

As best shown in Fig. 3, the diaphragm forming the subject matter of this inven-

tion consists of a layer 4 of textile fabric. We have found in practice that double-faced brown satin is particularly suitable for our purpose, owing to its appearance and construction. Arranged at the rear of the fabric layer, is a layer 5 of thin metallic foil, preferably tin foil, and arranged rearwardly of this layer is a third layer of dampening material, such as cork. This layer is of smaller size than the other 2 layers to permit free vibration of the diaphragm.

In manufacturing this diaphragm, the three layers, while in a flexible condition are pressed together and dried by heat, and in actual practice, we have built up a diaphragm of this character, in the following way:

We used one thin circular piece of cork ^{3/4} inch in diameter; one circular layer of tin foil of larger diameter rolled very thinly; and one layer of double-faced satin treated on both sides with quick drying French varnish. The layers were superposed, and adhesive placed between the tin foil and cork, and then the laminations were pressed together and dried by heat. The resulting diaphragm was placed in a reproducer casing and was found to produce improved results, reproducing sound more sharply and softly than the diaphragm now on the market.

From the foregoing it is believed that the method of manufacture, and the improved construction may be clearly understood, and it is obvious that changes may be made in the details disclosed without departing from the spirit of the invention as expressed in the claims.

What is claimed and desired to be secured by Letters Patent is:

1. A laminated diaphragm for sound reproducers comprising at least three layers, one layer of textile fabric, one of metallic foil, and one of sound dampening material, and adhesive securing said layers together.

2. A laminated diaphragm for sound reproducers comprising at least three layers, one layer of textile fabric, one layer of metallic foil, and one layer of cork, the cork

layer being of smaller diameter than the other layers, and adhesive securing said layers together.

3. A laminated diaphragm for sound reproduction comprising at least three layers, one outer layer formed of double-faced satin coated on both sides with varnish, the other outer layer being of smaller size and

formed of cork, and the intermediate layer formed of tinfoil, and adhesive securing said layers together.

In testimony whereof we affix our signatures.

JOHN Q. SLYE.
RICHARD H. COFFREN.
